UNITED STATES PATENT OFFICE

95,226

DESIGN FOR AN ELECTRIC LIGHTING FIXTURE

R. Guy Cowan, Syracuse, N. Y., assignor to Pass
& Seymour, Inc., Syracuse, N. Y., a corpora-
tion of New York

Application December 21, 1934, Serial No. 54,526

Term of patent 7 years

To whom it may concern:

Be it known that I, R. Guy Cowan, a citizen of the United States and resident of Syracuse, county of Onondaga, and State of New York, have invented a new, original, and ornamental Design for an Electric Lighting Fixture, of which the following is a specification, reference being had to the accompanying drawing, forming a part thereof, and in which:

Figure 1 is a perspective view of the assembled bracket and shade forming the fixture of the present design;

Figure 2 is a side elevation thereof; and

Figure 3 is a front elevation thereof.

I claim:

The ornamental design for an electric lighting fixture substantially as shown.

R. GUY COWAN.
